(57) **CLAIM**

The ornamental design for a water filled barbell, as shown and described.

DESCRIPTION

FIG. 1 is a front elevational view of a water filled barbell, the rear elevational view being a mirror image of the front view. FIG. 2 is a top plan view thereof.

FIG. 3 is a bottom plan view thereof;

FIG. 4 is a left side elevational view thereof, the right side elevational view being a mirror image of the left side view.
